THREE-PHASE SLOT ANTENNA SYSTEM

Robert S. Wehner, Port Jefferson, N. Y., assignor
to Radio Corporation of America, a corporation
of Delaware

Application February 28, 1946, Serial No. 650,952

12 Claims. (Cl. 250—33)

1

The present invention relates to short wave antennas and, more particularly, to such antennas for use on modern high speed airplanes.

An object of the present invention is the provision of an antenna for high speed airplanes which introduces no aerodynamic drag.

A further object of the present invention is the provision of an antenna for high speed airplanes which is entirely faired into the body of the fuselage or wing of the airplane.

A further object of the present invention is the provision of an ultra high frequency antenna having the following electrical characteristics:

1. A field pattern for horizontal polarization that is substantially uniform in the horizontal plane and in the hemisphere below the horizon.

2. Impedance characteristics such that the antenna may be matched with a less than 2:1 standing wave ratio to a 50 ohm line over a frequency band at least 10% wide.

The foregoing objects and others which appear from the following detailed description are attained in accordance with the principles of the present invention by providing a triangular arrangement of three thin rectangular slots cut in the conductive skin of the ship in either the fuselage or wing and backed by resonating cavities. The cavities are fed in a three-phase arrangement such that horizontally polarized energy is radiated in a substantially uniform field pattern and such that relatively flat input impedance characteristics are attained.

The present invention will be more fully understood by reference to the following detailed description which is accompanied by a drawing in which:

Figure 1 illustrates in a plan view a simple single rectangular slot and the radiating pattern in planes parallel to the mounting surface of said antenna, while

Figure 2 is a transverse cross sectional view of the antenna of Figure 1;

Figure 3 is a graph illustrating the variation in anti-resonant resistance of the antenna of Figure 1 with a variation in the placement in the feed point to the antenna.

Figure 4 is a field strength pattern showing the distribution of horizontally polarized energy in the plane of the antenna of the present invention;

Figure 5 is a family of curves illustrating the resistance-reactance characteristics of a single slot and a three-phase slot antenna over a band of frequencies, while

Figure 6 is a curve illustrating the band width of the antenna of the present invention;

Figures 7 and 8 illustrate in schematic form

2

two representative ways in which the antenna of the present invention may be energized, while

Figure 9 is a curve illustrating the relationship between the standing wave ratio on the branch lines of Figure 8 with reference to the input standing wave ratio on the main transmission line;

Figure 10 is a sectional view of the antenna of the present invention, while

Figure 11 is a transverse section taken along lines 11, 11 of Figure 10.

A simple faired-in slot antenna, suitable for use on aircraft, is shown in Figure 1. This includes a thin rectangular slot 12 cut in the conductive skin of the ship. The skin of the ship acts as a conductive ground plane and is denoted by reference letters GP. The minimum length L of the slot must be of the order of one-half wavelength at the operating frequency while the width W of the slot may be quite narrow, only $1/20$ or $1/30$ of a wavelength or less, so it is mechanically practical for use at frequencies in ultra high frequency ranges. Such a slot may be fed in a variety of ways, but one of the easiest methods involves backing the slot with a rectangular resonating cavity 14 (Figure 2) of the same cross section and a quarter wave in depth. This cavity may be fed from the coaxial cable TL, the outer conductor 16 of which is connected to one lengthwise wall of the cavity at some point on its vertical center line and the inner conductor 18 of which extends through cavity 14 to tie on to the opposite side wall.

Since the electric lines of force are directed across the cavity, parallel to the short sides, the radiating surface of the antenna may be regarded as the displacement current sheet across the slot aperture. The displacement current sheet is likewise polarized across the slot aperture. Consequently, the field pattern in planes parallel to that in which the slot is cut is linearly polarized in a direction transverse to the slot. The resultant radiation pattern, denoted by line 20 in Figure 1, is roughly a figure-eight with maxima in directions parallel to the slot and with minima in directions transverse to the slot. The degree of directivity is about the same as that existing in a plane containing a thin half wave dipole, the difference being that in the case of a dipole antenna, the maxima occur in directions transverse to the length of the antenna. It is apparent that a half wave slot such as shown in Figure 1 is as unsuitable for uniform horizontally polarized field patterns as a simple horizontal half wave dipole would be.

Aside from the radiational limitation mentioned above, the simple slot antenna of Figure 1 is marked by input impedance characteristics

which are intrinsically narrow band. It can be shown that the input impedances of a rectangular slot and of a flat strip dipole antenna, of the same cross section and fed in the same manner, are related by the expression $Z_1 Z_2 = (Z_0/2)^2$ where Z_1 and Z_2 are the input impedance of the slot antenna and the dipole antenna respectively and Z_0 is the impedance of free space. This equation forms a theoretical basis for two outstanding features of the slot antenna input impedance characteristics; that is, its high impedance level and the fact that it is anti-resonant rather than resonant. Since Z_0 , the impedance of free space, is equal to 377 ohms and since Z_2 is equal to 72 ohms, it follows from the above equation that the impedance on a corresponding slot antenna is of the order of 490 ohms. Furthermore, since the dipole has capacitive reactance below resonance and inductive reactance above resonance, the reverse must be true of a slot antenna. The input impedance characteristics of a slot 25 centimeters long, 1 centimeter wide, backed by a cavity of the same cross section and 8 centimeters deep, were measured for several positions of the feed transmission line TL over a range of frequencies extending from 900 to 1150 megacycles. One set of the resultant impedance data is graphically shown in Figure 5 wherein curve 25 illustrates the variation in resistance with a variation in the frequency while curve 26 illustrates the variation in reactance. These curves reveal the single slot antenna to be sharply anti-resonant with a high impedance level. Data run at other positions of the feed point, that is, at the other values of the ratio d/D , where d is the distance of the coaxial line from the top of the cavity (i. e. from the surface in which the slot is cut) and D is the depth of the cavity back of the slot, are qualitatively similar. The chief effect of feed position upon impedance characteristics is in terms of the impedance level, or value of the anti-resonant resistance of the system. As the feed is brought up from the bottom of the cavity, that is, where the ratio $d/D=1.0$, the resistance at resonance rises from zero to a high value, characteristic of the length and width of the slot relative to the operating frequency, at the top of the cavity; that is, where $d/D=0$. This dependence of anti-resonant resistance upon the ratio d/D for the particular slot system shown in Figures 1 and 2 is illustrated in the curve of Figure 3. The solid portion of line 28 illustrates the region over which measurements were actu-

or other standard low impedance lines over only relatively narrow frequency bands. For example, the 140 ohm slot radiator whose impedance characteristics are shown by curves 25 and 26 of Figure 5 when matched down to a 50 ohm transmission line by means of a conventional quarter-wave geometric mean transformer yields only 3.4% band width with less than a 2:1 standing wave ratio on a 50 ohm line. This is indicated by curve 30 of Figure 6. It might be expected that the simple slot antenna could be matched to a 50 ohm transmission line without the need for line matching sections merely by lowering the point of entry of transmission line TL into cavity 14 until a 50 ohm anti-resonant resistance, giving a direct match, is obtained, as is indicated by the data presented in Figure 3. However, substantially greater band width will not be obtained by this expedient, since the rate of variation of reactance with frequency is not reduced in any way near the same proportion as the anti-resonant resistance is lowered by bringing the feed closer toward the bottom of the cavity. The low impedance antenna is more reactive relative to the impedance level; that is, it has a much higher value of "Q" and therefore a smaller intrinsic band width than would be obtained by matching a high impedance slot down to a low level. Greater band widths might possibly be realized by use of complicated matching sections but it is believed that any single slot antenna system of the type shown in Figure 1 is incapable of yielding as much as 10% band width with less than 2:1 standing wave ratio on a standard 50 ohm cable.

Now consider a delta shaped array of antenna slots such as those indicated in the diagram at the center of Figure 4 wherein the slots are identified by reference characters 41, 42 and 43. This arrangement, with the displacement-current sheets across the slot apertures represented by suitably averaged current filaments directed across the centers of the respective apertures, may be regarded as analogous to a triole consisting of equispaced radial linear radiators. By assuming sinusoidal current distribution in the arms of the equivalent triole and calculating the individual distant fields of the component antennas and superposing the component fields the resultant distant field of the array may be obtained. For the special case of antennas quarter wave long, the field in the plane of the array may be shown to be given by the following expression:

$$E_\theta = [(E_1 + RPE_2 + RPE_3)^2 + (IPE_2 + IPE_3)^2]^{\frac{1}{2}} \quad (1)$$

where

$$E_1 = \frac{1}{\sin \theta} [1 + \cos^2 \theta - 2 \cos \theta \sin (90^\circ \cos \theta)]^{\frac{1}{2}} \quad (2)$$

$$E_2 \approx \frac{1}{\sin (\theta - 120^\circ)} [1 + \cos^2 (\theta - 120^\circ) - 2 \cos (\theta - 120^\circ) \sin (90^\circ \cos (\theta - 120^\circ))]^{\frac{1}{2}} \left(-\frac{1}{2} - J \frac{\sqrt{3}}{2} \right) \quad (3)$$

and

$$E_3 \approx \frac{1}{\sin (\theta - 240^\circ)} [1 + \cos^2 (\theta - 240^\circ) - 2 \cos (\theta - 240^\circ) \sin (90^\circ \cos (\theta - 240^\circ))]^{\frac{1}{2}} \left(-\frac{1}{2} + J \frac{\sqrt{3}}{2} \right) \quad (4)$$

ally made, the dashed portion of the line representing reasonable extrapolations.

Partly because of the high impedance level but principally because of the steepness of the reactance-frequency characteristics in the vicinity of anti-resonance as shown by curve 26 in Figure 5 slot antennas may be matched to 50 ohm

70 where

RPE_2 signifies Real Part of E_2

IPE_2 signifies Imaginary Part of E_2 , etc.

Equation 1 gives the relative field strength in the plane of the array as a function of the azimuthal angle θ , and is plotted in Figure 4 as curve

45. It will be noted that curve 45 is very nearly circular, exhibiting an even greater degree of circular, exhibiting an even greater degree of circular symmetry than is yielded by a turnstile array; that is, by two crossed dipoles fed in phase quadrature. Such arrays of linear radiators have been commonly used heretofore in applications calling for uniform distribution of horizontally polarized radiation, but the application of this principle to slots is believed to be new. It will be noted that in the plane of the slots the polarization is linear but rotates with the carrier frequency. In the direction normal to the plane the polarization is circular, while in intermediate directions the polarization is elliptical.

The field pattern shown in Figure 4 is not affected by moderate deviations from resonant frequency. The three-phase antenna yields substantially the same pattern over the entire range over which its input impedance characteristics are such that it may be matched to a standard transmission line, that is, input impedance rather than pattern characteristics will limit the useful band width of the antenna.

It is readily evident that if n antennas of equal input impedance Z_a are to be fed with currents of equal magnitude in n -phase relationship from a matched main transmission line of characteristic impedance Z_0 , the individual input impedances Z_a must equal nZ_0 and the individual antennas must be fed by the equivalent of branch lines of characteristic impedance nZ_0 , each successive branch line differing in length from the preceding by

$$\frac{360}{n}$$

degrees. This result may be attained in two slightly different mechanical arrangements. The two arrangements are schematically illustrated in Figures 7 and 8.

In Figure 7, for example, the main transmission line TL , having characteristic impedance Z_0 , is directly connected across the first antenna identified by reference numeral 50, having an input impedance of $3Z_0$. In shunt across this antenna and across transmission line TL is connected a second section of transmission line TL_1 having an electrical length of 120° and having a characteristic impedance equal to $1.5Z_0$. This section of transmission line TL_1 leads to the second antenna 51, likewise having an input impedance of $3Z_0$ and to a second section of transmission line TL_2 , likewise having an electrical length of 120° and having a characteristic impedance of $3Z_0$. Transmission line TL_2 is terminated by its connection to the third antenna 52 having an input impedance of $3Z_0$.

The alternative arrangement shown in Figure 8 employs three physically separate and distinct transmission line sections TL_1 , TL_2 and TL_3 . These three sections of transmission lines are all connected in parallel at one end and at the other ends are directly connected to antennas 50, 51 and 52. As before, the antennas each have an impedance $3Z_0$. Each of the transmission lines has a characteristic impedance equal to $3Z_0$ and they differ in length by 120 electrical degrees. In the event that the individual antennas 50, 51 and 52 are not perfectly matched to the individual branch lines; which will be the case if the system is to operate over an appreciable range of frequencies; perfect n -phase feeding will no longer exist and this may be expected to have at least some adverse effect both on the field pattern and on the input impedance of the array.

However, this effect is much smaller than might be expected. In the case of three identical antennas fed in three-phase relationship, it can be shown that if k is the magnitude of the reflection coefficient due to mismatch on the individual branch lines, and if K is the magnitude of the reflection coefficient due to the mismatch on the main feed line, then these two quantities are related by the expression $K=k^3$. Since the magnitude of the reflection coefficient is by definition less than unity it is evident that three-phase feeding has a pronounced broad banding effect. In terms of the standing wave ratio, more commonly used as a measure of mismatch, the above expression is equivalent to

$$S = \frac{(s^2 + 3s)}{(3s^2 + 1)}$$

where S is the standing wave ratio on the main line and s is the standing wave ratio on the branch lines. This expression is plotted in Figure 9 and indicates that the standing wave ratio on the branch lines, plotted as abscissae, can become quite high before the standing wave ratio on the main line, plotted as ordinates, becomes appreciably greater than unity.

While the main line reflection coefficient decreases as the cube of that existing on the branch lines only at or near the resonant frequency, that is, at that frequency at which the length of the branch lines are proper, the three-phase system has compensating tendencies over an appreciable range of frequencies to either side of resonance. That such compensating tendencies are appreciable even with a system involving individual antennas as inherently narrow band as the simple slot antenna of figure (Z) is demonstrated by curves 54 and 55 of Figure 5. These curves were calculated from measured input impedance data for a single 140 ohm slot antenna input impedance, combined in a three-phase arrangement. It is evident by comparing curves 54 and 55 with 25 and 26 which relate to a single slot antenna that the input impedance of the three-phase array is much flatter than that of the component antennas. The band width of a three-phase array fed directly without an external matching section is 15.2% with less than a $2:1$ standing wave ratio on a 50 ohm line as is shown by curve 56 of Figure 6, as compared with the 3.4% for a single slot and matching section as shown by curve 30.

In the foregoing example of the broad banding effect of three-phase feed on slot antennas, the possibility of interaction between the individual slots has been ignored. This is not a serious objection to the arrangement, however, since it is evident, from considerations of symmetry and the fact that all three slots are identical, that the mutual impedances between any pair of slots in the array is the same as that existing between any other pair of slots. Furthermore, the input impedance of any one slot in the array is equal to the difference between the self-impedance of that slot, that is, its input impedance when mounted by itself in a large ground plane, and the mutual impedance between any pair of slots. So regardless of the magnitude of the mutual impedances between the slots their input impedances are identical.

Of course, it is not sufficient that the individual input impedances of the component antennas be identical. They must also be equal to three times the characteristic impedance of the main transmission line. However, this makes little

difference as far as the practical use of the antenna is concerned since any input impedance between zero and 400 or more ohms, the upper value depending mainly upon the length, and secondarily upon the width of the slot, may be obtained with slot antennas simply by properly locating the feed in the side wall of the associated cavity. Thus the effect of mutual impedance between the slots may be compensated for merely by adjusting the position of the feed. Furthermore, since the slots are identical to begin with and since the effect of mutual interaction is the same on each, all three feed positions may be adjusted simultaneously, thus reducing the amount of trial and error adjustment necessary to achieve a balanced result.

As far as the pattern considerations alone are concerned it is of no importance whether the three slot antennas are arranged radially or along the sides of a triangle as shown in Figure 4. However, it is easier for geometrical reasons to feed three slots in a delta formation than in a radial arrangement and this arrangement may therefore be considered a preferred embodiment. Figure 10 represents a plan view of such an arrangement, the viewing plane being parallel to the conductive sheet in which the slots are cut, the plane being so chosen as to contain the centers of the feeds of the individual slots. The individual slots are backed up by cavities 60, 62 and 64 having the same transverse dimensions as the slots and approximately a quarter wave in depth. The cavity 64 carries on one side wall an input cable connector TLC having a threaded outer sleeve 66, and an inner conductor jack 68 of conventional form and configuration whereby the standard coaxial line cable fitting may be directly connected thereto. The inner conductor 68 is extended through cavity 64 and continues as inner conductor 70, surrounded by outer shell 71, thus forming a coaxial transmission line. Preferably, for reasons to be explained later, said line has an electrical length of 120 degrees and a characteristic impedance of 70 ohms. The said inner conductor 70 eventually passes through cavity 62 and terminates on the opposite side of cavity 62 in a stub tuning section of coaxial transmission line having an outer shell 75 and an inner conductor 76. An adjustable shorting plug 78 is provided for varying the electrical length of the tuning stub included in shunt across slot 62. The coaxial arrangement between conductor 76 and outer shell 75 is maintained by suitable insulating spacer 80 constructed of a low loss dielectric such as polyethylene or polystyrene. At the point where conductor 70 passes into slot 62 an inner conductor 72 branches off and being surrounded by outer shell 73 forms a feed line for cavity 50. Said feed line like that formed by conductors 70 and 71 has an electrical length of 120 degrees. The diameters of conductors 72, 73 are so proportioned as to provide a characteristic impedance of 140 ohms. Conductor 72, after passing through cavity 60, is terminated in an end stub 82, the conductor 72 being connected electrically to the end of the outer shell 82 of stub 82.

As shown in Figure 11 the feed plane of the antenna is located far enough above the base of cavities 60, 62 and 64 array that the input impedances of the separate slots, allowing for the effect of interaction are each equal to 140 ohms, although any figure between 135 and 165 would be satisfactory for a delta slot system fed from a 50 ohm coaxial line. The system is thus approxi-

mately equivalent to three 140 ohm impedances fed in parallel so the overall input impedance is approximately one third of 140 or 47 ohms, close enough to 50 ohms so that the system is fairly well matched at mid band. Since the line lengths to the various slots differ by 120 degrees a rotating radiation field is set up.

If desired, the input connector TLC can be located on the inner wall of cavity 64 rather than on the outer wall as shown in Figure 10. The outer wall is preferable, from the standpoint of convenience in making connections to the transmitter. Since cavity 64 is thus fed in a different manner from cavities 60 and 62 some slight discontinuity effect will be noted. To compensate for this, the outer wall connections of cavities 60 and 62 are provided with the respective fixed and adjustable tuning stubs heretofore described.

While the geometry of an equilateral triangle imposes some limitation on the maximum length of the slots of the antenna consistent with a feed system shown in Figure 10, the restriction is not severe. If air-dielectric cavities and lines are used, the maximum slot length is approximately $\frac{3}{4}$ of the operating mid-band wavelength. Since low frequency cut-off will not occur until the wavelength is such that the slot is of the order of half-wave long, it is evident that the slot may deviate from resonance by at least 24% to either side before the system becomes inoperative due to insufficient slot length. A potential band width of at least 48% is considerably larger than that over which the impedance characteristics will be satisfactory.

The cavities 60 and 62 are preferably closed by thin conductive window 85 (Figure 11) of polystyrene or other low loss dielectric material. The particular manner of securing the closure whereby the cavities are rendered proof against the entry of moisture and the like, shown in Figure 11, is merely illustrative and other means may be used if desired. However, it is comparatively simple to provide window portions 85 with dependent formed flanges 86. The flanges may easily be screwed or cemented on to the side walls of the cavity.

While I have illustrated a particular embodiment of the present invention, it should be clearly understood that it is not limited thereto since many modifications may be made in the several elements employed and in their arrangement without departing from the spirit and scope of the invention.

What is claimed is:

1. An antenna system including a number of elongated narrow slots in a conductive sheet, said slots being arranged in a polygonal formation, a conductive walled cavity back of each slot, a source of high frequency energy and a multi-branch transmission line connecting said source to each of said cavities, the lengths of the connections from said source to said cavities so differing that a rotating field is radiated.

2. An antenna system including a number of elongated narrow slots in a conductive sheet, said slots being arranged in a delta formation, a conductive walled cavity back of each slot, a source of high frequency energy and a multi-branch transmission line connecting said source to each of said cavities, the lengths of the connections from said source to said cavities so differing that a rotating field is radiated.

3. An antenna system including a number of elongated narrow slots in a conductive sheet,

said slots being arranged in a delta formation, a conductive walled cavity back of each slot, a source of high frequency energy and a multi-branch transmission line connecting said source to each of said cavities, the lengths of the connections from said source to said cavities so differing that a rotating field is radiated, the height of the point of entry of said connections into said cavities being so chosen that the impedance presented at said connections by said cavities is equal to the impedance of said connections.

4. An antenna system including a number N of elongated narrow slots in a conductive sheet, said slots being arranged in a regular geometric pattern, a conductive walled cavity back of each slot, a source of high frequency energy and a multi-branch transmission line having a primary section of Z_0 ohms characteristic impedance and branch sections connecting said source to each of said cavities, the lengths of the connections from said source to successively energized cavities differing by

$$\frac{360}{N}$$

degrees whereby a rotating field is radiated, the height of the point of entry of said connections into said cavities being so chosen that the impedance presented at said connections by each of said cavities is N times the characteristic impedance of the said primary section of transmission line, or equal to the characteristic impedances NZ_0 ohms of said branch sections.

5. An antenna system including a number of elongated narrow slots in a conductive sheet, said slots being arranged in delta formation, a conductive walled cavity back of each slot, a coaxial transmission line from high frequency energy transducer means, the inner conductor of said line being coupled to each of said cavities in turn to energize the same, the length of line between successively energized cavities being such that a rotating field is radiated.

6. An antenna system including a number of elongated narrow slots in a conductive sheet, said slots being arranged in delta formation, a conductive walled cavity back of each slot, a coaxial transmission line from high frequency energy transducer means, the inner conductor of said line being coupled to each of said cavities in turn to energize the same, the length of line between successively energized cavities being such that a rotating field is radiated and the characteristic impedance of said transmission line so differing between successively energized cavities that the impedance of the transmission line at any point is equal to the resultant parallel impedance of the first succeeding cavity and the succeeding portions of the system remote from said transducer means.

7. An antenna system including a number N of elongated narrow slots in a conductive sheet, said slots being arranged in a regular geometric pattern, a conductive walled cavity back of each slot, a coaxial transmission line from a high frequency energy transducer means, the inner conductor of said line being coupled to each of said cavities in turn to energize the same, the length of the line between successively energized cavities being

$$\frac{360}{N}$$

electrical degrees and the characteristic impedance of said transmission line so differing between successively energized cavities that the impedance of the transmission line at any point is equal to

the resultant parallel impedance of the first succeeding cavity and the succeeding portions of said system remote from said transducer means.

8. An antenna system including a number N of elongated narrow slots in a conductive sheet, said slots being arranged in a regular geometric pattern, a conductive walled cavity back of each slot, a coaxial transmission line from a high frequency energy transducer means, the inner conductor of said line being coupled to each of said cavities in turn to energize the same, the height of said line in said cavities being such as to present to said line an impedance N times that of said line, the length of the line between successively energized cavities being

$$\frac{360}{N}$$

electrical degrees and the characteristic impedance of said transmission line so differing between successively energized cavities that the impedance of the transmission line at any point is equal to the resultant parallel impedance of the first succeeding cavity and the succeeding portions of said system remote from said transducer means.

25 9. An antenna system including a number N of elongated narrow slots in a conductive sheet, said slots being arranged in a delta formation, a conductive walled cavity back of each slot, a source of high frequency energy and a multi-branch transmission line connecting said source to each of said cavities to energize the same, the lengths of the connections from said source to successively energized cavities differing by

$$\frac{360}{N}$$

35 electrical degrees whereby a rotating field is radiated.

40 10. An antenna system including a number N of elongated narrow slots in a conductive sheet, said slots being arranged in delta formation, a conductive walled cavity back of each slot, a coaxial transmission line from high frequency energy transducer means, the inner conductor of said line being coupled to each of said cavities in turn to energize the same, the length of line between successively energized cavities being such that a rotating field is radiated, said transmission line being terminated in an adjustable short-circuited tuning stub whereby the feed to said cavities may be equalized.

45 11. An antenna system including three elongated narrow slots in a conductive sheet, said slots being arranged in delta formation, a conductive walled cavity back of each slot, a coaxial transmission line from high frequency energy transducer means to energize said cavities, the inner conductor of said line passing through the first and last of said cavities and having a branch connection passing through the second of said cavities, the length of line between successively energized cavities being such that a rotating field is radiated and the characteristic impedance of said transmission line so differing between successively energized cavities that the impedance of the transmission line at any point is equal to the resultant parallel impedance of the first succeeding cavity and the succeeding portions of the system in the direction of said last cavity, 50 said second and last cavities being provided with short-circuited tuning stubs connected to said line whereby the feed to said cavities may be equalized.

55 12. An antenna system including a number of elongated narrow slots in a conductive sheet, said slots being arranged in a polygonal formation in

said sheet, a conductive walled cavity back of each slot, a transmission line from high frequency energy transducer means, a conductor of said line being coupled to each of said cavities in turn to energize the same, the length of line between 5 successively energized cavities being such that a rotating field is radiated.
